Primary Examiner — Janice Hallmark*Assistant Examiner* — Rodolfo Castro, Jr.(74) *Attorney, Agent, or Firm* — Birch, Stewart, Kolasch & Birch, LLP(57) **CLAIM**

The ornamental design for a display device for furniture, as shown and described.

DESCRIPTION

FIG. 1 is a front, right perspective view of a display device for furniture showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged detail view of encircled portion "8" of FIG. 1.

Broken lines illustrate portions of the display device for furniture that form no part of the claimed design.

1 Claim, 8 Drawing Sheets(56)
